UNITED STATES PATENT OFFICE.

CHARLES C. LODER, OF DAYTON, KENTUCKY, ASSIGNOR OF ONE-FOURTH TO GUSTAV HAFFNER, ONE-FOURTH TO LOUIS HAFFNER, AND ONE-FOURTH TO EDWIN HAFFNER, ALL OF CINCINNATI, OHIO.

FURNACE.

1,325,522.

Specification of Letters Patent. Patented Dec. 23, 1919.

Application filed March 3, 1919. Serial No. 280,272.

To all whom it may concern:

Be it known that I, CHARLES C. LODER, a citizen of the United States of America, and a resident of Dayton, in the county of Campbell and State of Kentucky, have invented a new and useful Improvement in Furnaces, of which the following is a specification.

My invention relates to that class of furnaces, which are divided by a central dia-
10 phragm into two combustion chambers for the flow of gases, communication between which may be had between the grate bars and the diaphragm.

An object of my invention is to provide
15 a furnace of this class, in which heated air is supplied to the partly consumed gases in their passage from one combustion chamber to the other, so that as the heated gases and the air pass up through the glowing coals
20 in the other chamber perfect combustion of the gases is had.

Another object of my invention is to pro-
25 vide a means for regulating the supply of air to the furnace.

Another object of my invention is a ready
30 means for changing the direction of the passage of gases from the furnace to the flue.

Another object of my invention is to pro-
35 vide a furnace of this kind with a dia-
phragm section which may be readily in-
stalled in a furnace.

These and other objects are attained by
40 the means described in the specification and illustrated in the accompanying drawings,
35 in which:—

Figure 1, is a perspective view of a hot air furnace embodying my invention, parts of the air jacket and the body being shown broken away, and the partition or dia-
45 phragm being shown partly in section.

Fig. 2, is a central transverse sectional view of the same.

Fig. 3, is a detail side elevation of the dia-
45 phragm.

Fig. 4, is a top plan view of the dia-
phragm.

Fig. 5, is a front elevation of the auxiliary dia-
phragm which supplies air to the dia-
phragm.

Fig. 6, is a detail front elevation of the dia-
phragm and of the dampers which regu-
late the direction of the passage of air to the smoke box.

Fig. 7, is a detail front elevation of the
55 furnace and of the furnace doors.

Referring to the parts; body A of the furnace is surrounded by the usual housing A', for forming the hot air jacket around the furnace body. Within the ash pit A³, twin grate bars A⁴, A⁵, are pivotally mounted upon a common support rod A⁶, so that they may be independently shaken by means of links A⁷, A⁸, which are connected to handles upon the front of the housing A. The body of the furnace has a fuel feed opening, which is connected by means of a fuel feed box A¹⁰ with the front of the housing A'. The body of the furnace has extending from its top to within a short distance from the grates, a diaphragm which divides the body of the furnace into two combustion chambers A¹¹, A¹². The distance between the lower end of the diaphragm and the grates is such as to leave room for a shallow bed of coals. In the upper part of the body of the furnace is a rectangular opening which is surrounded by a smoke box G, which connects with the flue. The diaphragm is arranged centrally of the opening in the top of the furnace and the communication between the furnace and the smoke box is controlled by two dampers H, H', which are coupled together so that when one is closed the other one is open. When first fuel is fed upon the fire in the furnace, it is placed in the combustion chamber whose damper is closed. This forces the gases to flow down below the diaphragm and into the other combustion chamber, being combined in its passage with the heated air supplied by the diaphragm, and thence through the open damper to the smoke chamber.

I will now describe the details of the construction of the parts.

The diaphragm is composed of support plates c, c' whose upper edges are curved to fit the dome of the body of the furnace to which it is secured by bolts c². The plates have reduced upper ends which fit within the flange a⁴ which surrounds the opening in the top of the body of the furnace. Plate c' has flanges c³, which overlap the inner edge of plate c. To the lower edges of plates c, c', are secured plates c⁴, c⁵, c⁶, c⁷, the overlapping edges of the plates c⁴, c⁷ and plates c⁵, c⁶ are rabbeted and the edges overlap a sufficient distance to permit of an expansion of the plates under heat. The inner faces of these plates carry lugs 110

- which space plates c^4 , c^7 from plates c^5 , c^6 , so as to form an air space c^8 between them. The outer edges of plates c^4 , c^5 , c^6 , c^7 , contact closely with the walls of the body of 5 the furnace. The lower edges of these plates have substantial semicircular flanges c^9 , c^{10} , c^{11} , c^{12} , which form ways to receive the beads upon the upper ends of plates c^{13} , c^{14} , c^{15} , c^{16} . The inner edges of plates c^{13} , c^{14} , c^{15} , c^{16} , 10 likewise are rabbeted similarly to plates c^4 — c^7 . The lower edges of plates c^{13} , c^{14} , c^{15} , c^{16} , have in them a series of notches c^{18} . Plates c^{13} , and c^{14} are spaced from plates c^{15} , c^{16} , so as to leave between them an air 15 chamber c^{17} , which is in alinement with the air chamber c^8 . The lower sides of the diaphragm fit between lugs a , a' which project inward from opposite sides of the fire pot, as shown in Fig. 2.
- 20 Centrally located of the fuel feed box A^{10} , is an auxiliary diaphragm, which is composed of plates E , E' , between which is formed an air chamber e which communicates with the air chamber c^8 , at one end, 25 and at the outer end communicates with the external air by an opening e' , the opening and closing of which is controlled by a slide e^2 in the front wall of the box A^{10} . Plates E , E' , have at their rear ends flanges e^3 , 30 which overlap the front edges of plates c^6 , c^7 . Plates E , E' are held together by lugs e^4 , e^5 . The auxiliary diaphragm divides the fuel feed box A^{10} into two fuel feed passages, access to which is had by 35 doors F , F' .
- 40 Mounted upon top of the body of the furnace and surrounding the flange a^4 is a cylindrical smoke box G , which communicates with the pipe G' which leads to the flue.
- 45 The opening between the smoke box and the body of the furnace is divided in two by the main diaphragm. In said openings are mounted dampers H , H' . The dampers are mounted upon the longitudinal rods h , h' , which extend through the walls of the smoke box and receive upon their outer ends gears h^2 , h^3 , which are in mesh with a central gear wheel h^4 , which is secured upon a rod h^5 which is journaled in the smoke box and 50 the flange a^4 , extends through a housing A' and receives upon its end an arm h^6 by means of which the gear wheels h^2 , h^3 , h^4 , may be rotated to change the position of the dampers H , H' , which are so positioned 55 upon their mounting rods that when one is closed the other is open.
- 60 In operation the diaphragm of the combustion chamber, in which the fresher fuel is located, is kept closed. Therefore the gases therefrom must seek an outlet to the flue by passing beneath the diaphragm into the other combustion chamber. The slide e^2 being open, air passes through the opening e' into the air chamber e of the auxiliary diaphragm thence into the air chamber 65
- c^8 thence downward between the plates c^{13} , c^{14} , c^{15} , c^{16} , and is mixed with the gases passing beneath the diaphragm. The air in its passage through the auxiliary diaphragm and the main diaphragm, is heated by the 70 walls thereof so that it is in condition to assist in the combustion of the gases as they pass upward through the red coals in the second combustion chamber. After the coals in the first combustion chamber have 75 been somewhat consumed, fresh fuel is placed in the second combustion chamber, and the dampers H , H' , are reversed in their positions so that the flow of gas passes downward from the second combustion 80 chamber and into the first combustion chamber.
- To prevent the coal from forming a seal against the passage of air, along the lower edge of plates c^{13} — c^{16} , I have placed a series of lugs c^{19} , which assist the notches c^{18} , in forming air passages. 85
- Air is to be admitted above the fuel into the combustion chamber from which the flow of gas is taking place. The admission 90 of this air may be had by means of rotating slides f in the furnace doors F , F' . These rotating slides are of the ordinary construction such as commonly used for regulating admission of air through furnace doors, and 95 need not therefore be more specifically described. The slides f in the door of the fuel passage leading to the combustion chamber, through which the gases are passing upward to the smoke box, are kept closed. 100
- What I claim is:—
1. In a furnace the combination of a furnace body, a diaphragm with imperforate sides and dividing the body of the furnace into combustion chambers and having in it 105 an air chamber which communicates at its lower end with the combustion chambers, means for admitting external air to the air chamber, and dampers adapted to cause the gases from either combustion chamber to 110 flow beneath the diaphragm and into the other combustion chamber.
  2. In a furnace the combination of a furnace body having an opening in its top, a smoke box covering and encircling the opening, a central diaphragm extending into the opening, contacting with opposite walls of the body of the furnace and terminating at a distance above the grates, dividing the furnace into two combustion chambers, and 115 having in it an air passage adapted to discharge air into the space below it and dampers located in the opening in the top of the furnace and adapted alternately to close the communication between one combustion chamber and to open communication between the other combustion chamber and the smoke box and vice versa. 120
  3. In a furnace the combination of a furnace body a central diaphragm therein com- 130

prising plates contacting with and secured to the top of the furnace body, two sets of lower plates secured upon each side of the first mentioned plates and adapted to form 5 an air chamber between them, said plates having at their lower ends curved flanges and two sets of plates having beads mounted in the flanges and adapted to form an air passage leading from the air chamber into 10 the space below the diaphragm.

4. In a furnace the combination of a furnace body a housing surrounding the furnace body and forming a hot air chamber therewith, a furnace body having fuel feed 15 openings in its side and an opening in its top for the discharge of gas, a fuel feed box contacting with the body surrounding the fuel feed opening and extending through the housing, a smoke box mounted upon the 20 furnace body and surrounding the discharge opening in its top, a diaphragm dividing the furnace body into two combustion chambers and having therein a central passage dis-

charging into the space below the dia-
phragm, an auxiliary diaphragm extending 25
from the diaphragm through the fuel feed
box and having therein an air passage ex-
tending from the front of the furnace to the
air passage in the diaphragm, fuel feed
doors in the feed box and upon each side 30
of the diaphragm, dampers in the furnace
top adapted to regulate the flow of gas
from the combustion chambers to the smoke
box and means for moving the dampers.

5. In a furnace the combination of a fur-
nace body, a diaphragm dividing the body
into two combustion chambers and having
in it an air passage, the lower edge of the
diaphragm being serrated and having a se-
ries of lugs adjacent to the serrations and 40
adapted to coöperate with the serrations to
form air passages through the fuel.

In testimony whereof, I have hereunto
subscribed my name this 27th day of Feb-
ruary, 1919.

CHARLES C. LODER.
